[57] **CLAIM**

The ornamental design for a bottled water dispenser, substantially as shown and described.

DESCRIPTION

FIG. 1 is a top plan view of a bottled water dispenser showing my new design;

FIG. 2 is a top plan view of a second embodiment of that shown in FIG. 1;

FIG. 3 is a front elevational view thereof;

FIG. 4 is a side elevational view thereof, the water bottle shown in broken lines for illustrative purposes only; and

FIG. 5 is a rear elevational view thereof.
